DESIGN.

F. W. COPELAND.

COOKING STOVE OR RANGE.

No. 15,528.

Patented Nov. 11, 1884.

UNITED STATES PATENT OFFICE.

FREDERICK W. COPELAND, OF CHELSEA, MASSACHUSETTS.

DESIGN FOR A COOKING STOVE OR RANGE.

SPECIFICATION forming part of Design No. 15,528, dated November 11, 1884.

Application filed May 23, 1884. Term of patent 7 years.

To all whom it may concern:

Be it known that I, FREDERICK W. COPELAND, a citizen of the United States, residing at Chelsea, in the county of Suffolk and State 5 of Massachusetts, have invented and produced a new and original Design for Cooking Stoves or Ranges, of which the following is a specification, reference being had therein to the accompanying photograph, forming a part 10 thereof.

The accompanying photograph is a side and front view of my newly-designed cooking-range, and sufficiently illustrates my design.

Heretofore ranges have been made which in 15 general outline and plan have somewhat resembled this design; but the resemblance is only general.

The leading feature of my design consists of a range with a flue, A, side wings or brackets, 20 B B', and back of top shelf, C D, but highly ornamented in relief, as shown in the accompanying photograph. The flue A is ornamented with a panel in which is a central rosette or conventionalized sunflower surrounded by conventionalized laurel stems, leaves, and berries. The side wings or brackets are 25 ornamented with the same design, terminating in a scroll, B'. The back guard of top shelf, D, is ornamented by a beaded molding, with

the same rosette, C, resting on a bed of conventionalized laurel leaves, vines, and berries in the center. The several doors have raised surfaces ornamented with panel-work and moldings. The small stove-door E is ornamented by a design in the form of a medallion 35 composed of two hearts, the indentations toward each other, the points turned to the right and left, as shown in the accompanying photograph.

I have detailed my design in words so far as 40 I can, but the best description is the photograph herewith.

I claim—

1. The design for a stove having the ornamentation of a flue, side wings or brackets, 45 and back guard of top shelf at the back of and surmounting a range, the same consisting of raised figures or conventionalized flowers, vines, leaves, and berries, substantially as set forth and described.

2. The design for a range, as shown and described.

In testimony whereof I affix my signature in presence of two witnesses.

FREDK. W. COPELAND.

Witnesses:

L. C. SOUTHARD,
J. A. O'NEIL.
